9264X

G. Richards,

Fire Place.

No. 9,264 X

Patented Nov. 25, 1835.

Gilbert Richards, Ashfield Massachusetts
Letters Patent.

The Schedule referred to in these Letters Patent and making part of the same containing a description in the words of the said Gilbert Richards himself of his improvement in the steel iron fire place or frame

to whom these presents shall come. To all known that of Gilbert Richards of Ashfield in the County of Franklin and State of Massa-
chusetts have invented a new and useful article called a fire frame
made of Steel iron, and that the following is a full and exact descrip-
tion of the construction and use of the said frame as invented and
improved by me to wit. 1st Take a plain piece of Steel iron about
ten feet wide, with a little more or a little less and of any height
suitable for the fire place in which the frame is designed to be placed.
Then on the front edge of this piece of Steel iron with a proper in-
strument or machine make a roll or cylinder, this makes the main
part of one side of the said frame, the other side is like & made the
same way, only the cylinder turns a contrary way. These sides
may be either straight or scalloped. Then construct a cap for the sides
of the frame, the right and left hand edge turned down in width
about one and a half inches for the purpose of holding together the sides
of the frame. The front edge of the cap is to be about one foot wide
than the back and bent over in front about six inches to form
a Mantle, the lower edge of the Mantle having a small iron roll-
ed in and the ends of the wire inserted into the cylinders.
Then make two straps of steel iron or other metal, about one
inch and a half wide, placed near the top of the frame fastened
in with bolts or nuts & screws passing through the right & left
hand edges of the cap turned down and the upper part of the sides
of the frame for the purpose of giving the frame strength & holding
it together. Over the upper ends of the cylinders put caps with holes
in the centres for iron rods to pass down through the cylinders
the lower ends of the iron rods are to be fastened into holes drilled

into the head of the fine planed end or otherwise the rods must have also screws & nuts on the other ends which can be screwed down so as to make the frame firm.

The crane eye for the piano can be laid upon flat into the nail back & cut in the fine place. or crane eyes may be used described as follows. to wit: The upper eye may be fastened to the old eye by a hook ^{and} twisted out sufficiently so that it may be turned in through the frame. The lower eye hooked to the upper and extended in front sufficiently to admit the crane. All I claim as a patent is the making of the frame first but in a manner described.
